PAGE 4

FIG-4

F-29-5

FIGURE 1 is a top plan view of a game board, showing my new design;

FIGURE 2 is a top plan view of the upper left hand quarter of the game board of FIGURE 1, on an enlarged scale for purposes of clarity;

FIGURE 3 is a top plan view of the upper right hand quarter of the game board of FIGURE 1, on an enlarged scale for purposes of clarity;

FIGURE 4 is a top plan view of the lower left hand quarter of the game board of FIGURE 1, on an enlarged scale for purposes of clarity; and

FIGURE 5 is a top plan view of the lower right hand quarter of the game board of FIGURE 1, on an enlarged scale for purposes of clarity.

The game board is of conventional thickness.

I claim:

The ornamental design for a game board, as shown and described.
